UNLOADING MACHINE

Walter V. Inman, Obion, Tenn., assignor of one-half to Margaret Inman Wood, Memphis, Tenn.

Application September 20, 1944, Serial No. 554,957

2 Claims. (Cl. 214—44)

The device forming the subject matter of this application is adapted to be employed for unloading sand and other similar materials from a gondola railroad car into a truck disposed at one side of the railroad car. The invention aims to provide novel means for elevating the sand or other material in the car, carrying it laterally, and depositing it in the truck. The invention aims, further, to provide novel mechanisms for driving those parts which need actuation. A further object of the invention is to provide novel means for moving the device longitudinally of the railroad car as the sand is taken out of the car.

Within the scope of what is claimed, the structure described and shown may be changed, without departing from the spirit of the invention.

In the drawings:

Figure 1 shows in top plan, a device constructed in accordance with the invention;

Figure 2 is a longitudinal section on the line 2—2 of Figure 1;

Figure 3 is a transverse section on the line 3—3 of Figure 2;

Figure 4 is a detailed view showing a portion of the means whereby the conveying mechanism is moved longitudinally of the car.

In the drawings, the forward end of the railway car 1 is designated by the letter A, the rear end thereof being marked by the letter B.

The numeral 1 designates a railway car of the gondola type. A carriage C is mounted to move longitudinally of the box-like body of the car 1 and includes inverted trough shaped guides 2, carried slidably on the upper edges of the side walls of the car body. Hollow end members 3 are secured to the forward portions of the guides 2.

As shown in Figure 2, upstanding brackets 4 are secured to the rear portions of the guides 2, a baffle plate 5 being mounted fixedly on the brackets 4 and extending transversely of the car 1. A transverse conveyor shaft 6 is journaled in the end members 3 of the carriage C. To one end of the conveyor shaft 6, a sprocket wheel 7 is secured. The sprocket wheel 7 is engaged by a depending sprocket chain 8, engaged detachably with a sprocket wheel 9, secured to the ground wheel 10 of a truck 11 located along side the car 1, the rear end of the truck being jacked up by any suitable mechanism shown at J.

Links 12 are supplied, and are made longitudinally extensible by any suitable means indicated at 19, the links being of longitudinal

extensible construction, in order that the mechanism may be adjusted to gondola cars of different depths. The lower ends of the links 12 carry forks 16, wherein axles 14 are mounted, sprocket wheels 15 being rotatably carried by the axles, within the forks. Sprocket wheels 17 are secured to the transverse conveyor shaft 6. Depending endless conveyors 18 are carried by the sprocket wheels 15 and 17, and extend downwardly into the car 1 to places closely adjacent to the bottom of the car. The specific form of the conveyors 18 is a manufacturer's choice.

Longitudinal conveyor shafts 20 are journaled in the end members 3 and in bearings 21 on the rear portions of the guides 2. Worm wheels 22 are secured to the shafts 20, within the end members 3. The worm wheels 22 mesh with worms 23, located within the end members 3, and secured to the transverse conveyor shaft 6.

10 The conveyor shafts 20 carry sprocket wheels 24, about which is engaged a transversely operating belt conveyor 25.

As to the operation of the structure thus far described, the wheel 10, driven by the engine 25 (not shown) of the truck 11 operates the sprocket chain 8 through the instrumentality of the sprocket wheel 9, rotation being imparted to the shaft 6 by way of the sprocket wheel 7. When the shaft 6 is rotated, as aforesaid, the endless conveyors 18 will acquire sand or other material from the car 1 and carry it upwardly, the sand being cast rearwardly upon the transverse belt conveyor 25, or against the baffle plate 5, which returns the material to the conveyor.

35 From the shaft 6, rotation is imparted to the conveyor shafts 20, by way of the worms 23 and the worm wheels 22, the conveyor 25 being actuated to carry the material laterally and deposit it in a chute 26, supported on the car 1 and on the truck 11 and discharging into the truck.

40 From the foregoing it will be evident that means is provided whereby the material in the car 1 may be gathered up and discharged into truck 11.

45 As the material is carried out of the car 1, it becomes necessary to advance the carriage C, in order that the conveyors 18 may cooperate properly with the material remaining in the car.

50 As a means to that end, flexible elements 27 are secured at 28 to the end members 3 of the carriage C. The flexible elements 27 extend lengthwise of the car 1 and are wound about drums 29 secured to a transverse shaft 30 journaled bearings 31, the bearings including clamp-

ing means 32 which hold them detachably on the forward end wall of the car.

Comparing Figures 4 and 1, a ratchet wheel 33 is secured to one end of the shaft 30. A casing 34 is mounted to rock on the shaft 30 and encloses the ratchet wheel 33, the casing 34 having a depending handle 35. A pawl 36 is pivoted to the casing 34 and cooperates with the ratchet wheel 33.

By swinging the handle 35 to and fro, rotation is imparted to the ratchet wheel 33 by way of the pawl 36, rotation is imparted to shaft 30, the drums 29 are rotated, the flexible elements 27 are wound about the drums, and the carriage C is advanced, to the end that the depending conveyors 18 may obtain a new hold on the material within the car 1.

The device forming the subject matter of this application is simple in construction, but it will be found thoroughly advantageous for the ends in view. The construction is such that the mechanism may be removed from the car 1 and be transported readily to another car, as occasion may require.

I claim:

1. Unloading mechanism comprising a carriage including approximately parallel guides constituting means whereby the carriage may be mounted on a car for movement therealong, end

members carried by the guides, a transverse operating shaft journaled in the end members, a depending endless conveyor carried by and operated by the shaft, a transverse conveyor receiving material from the endless conveyor and disposed approximately parallel to the shaft, a baffle forming a connection between the guides, the baffle being disposed outwardly of the transverse conveyor and forming means for depositing on the transverse conveyor, material which may have been discharged on the baffle by the endless conveyor, the baffle being disposed approximately parallel to the shaft, and means for operating the shaft, the shaft and the baffle cooperating to maintain the guides in approximately parallelism.

2. Unloading mechanism constructed as set forth in claim 1, in combination with means for moving the carriage, said means comprising spaced bearings, means for mounting the bearings removably and individually on a car, a shaft journaled in the bearings, drums secured to the shaft and received in the bearings, flexible elements attached to the end portions of the carriage and wound about the drums, and manually operable means for rotating the last specified shaft.

WALTER V. INMAN.
